UNITED STATES PATENT OFFICE.

HENRY G. IRMIGER AND JAMES McCARTHY, OF GREEN BAY, WISCONSIN.

APPARATUS FOR MEASURING AND MIXING LIQUIDS.

SPECIFICATION forming part of Letters Patent No. 659,066, dated October 2, 1900.

Application filed June 26, 1899. Renewed April 19, 1900. Serial No. 13,514. (No model.)

To all whom it may concern:

Be it known that we, HENRY G. IRMIGER and JAMES McCARTHY, citizens of the United States, residing at Green Bay, in the county 5 of Brown and State of Wisconsin, have invented new and useful Improvements in Apparatus for Measuring, Diluting, and Mixing Washing Compounds, of which the following is a specification.

10 The object of our invention is to provide an apparatus which may serve as an attachment for washing-machines, by means of which the washing compounds or chemicals employed may be accurately measured, diluted, and 15 mixed with water and fed into the washing-cylinder, all without the use of measuring-cans and the like and without danger of spilling the same.

The invention consists of a diluting and 20 mixing cylinder, an agitator in said cylinder, a series of tanks or containers for the different chemicals, having valved communication with said cylinder, and measuring devices on said tanks.

25 It also consists in certain details of construction and combinations of parts, which will be hereinafter more fully described and claimed.

In the drawing forming part of this specification the figure is a sectional side elevation.

Our improved device is made up of a mixing and diluting cylinder 1, adapted to be suitably supported adjacent to the washing-machine and having a discharge-pipe 2 leading therefrom, provided with a cock or cut-off 3 and communicating with the washing-machine. The said cylinder is further provided with a valved inlet-pipe 4, through which hot or cold water, or a mixture of both, 35 may be admitted to the interior. The quantity of water in the cylinder may be determined by the gage 5. On the inside of the cylinder 1 is an agitator 6 in the form of paddles or blades, having openings 7 therein and 40 secured to a central shaft 8, which has one end extended through the cylinder-head and is provided with a crank 9.

Above the cylinder 1 is a series of cylindrical tanks 10, 11, 12, 13, and 14, five being 45 shown, although it is obvious that there may be a greater or a smaller number, as occasion may require. These tanks contain the

chemicals or compounds which are used in cleansing the clothes. For example, the tank 10 may contain bluing, the tank 11 acid, the 55 tank 12 bleaching compound, the tank 13 ammonia, and the tank 14 solution of borax. Each of said tanks is provided with a filling-opening at its upper end and with a pipe 15 at its lower end, which leads through the wall 60 of the cylinder 1 and has a cock or cut-off 16 therein. Each of said tanks is further provided with a transparent measuring-tube 17, extending along the outside thereof, communicating with the interior of the tank at its 65 upper and lower ends and having graduations thereon indicating liquid ounces or other convenient units of measure.

Our apparatus is intended to be constructed of such size that the tanks or containers 70 10, 11, 12, 13, and 14 will hold enough chemicals to supply the washing-machine with which it is used for a period of about a week, so that refilling is required only at relatively long intervals. Starting with the tanks filled, 75 the operation of the device is as follows: Say, for example, it is desired to introduce two ounces of bluing to the washing-machine. The valve or cock in the inlet-pipe 4 is opened to admit the proper quantity of water into the 80 cylinder 1, the same being determined by the water-gage 5. The said valve or cock is then closed and the cock 16 in the pipe 15 opened to allow a portion of the contents of the tank 10 to flow into said cylinder. When the 85 measuring-tube 17 indicates that two ounces have passed from the said tank, the cock 16 is closed and the crank 9 on the shaft 8 turned. This action causes a rotation of the agitator 6, with the result that the bluing and water are 90 thoroughly mixed or commingled and are ready to be fed into the washing-machine. This latter step is carried out by opening the cock or cut-off 3 and allowing the mass to pass out of the cylinder 1 through the discharge-pipe 2. An operation similar to that above 95 described would be performed on the other tanks if different chemicals or compounds are desired.

From the foregoing description it will be 100 noted that we have provided an extremely simple and effective device by means of which the constant handling of chemicals is avoided and an accurate measurement and dilution of

the same are obtained prior to their introduction into the washing apparatus.

Having now described our invention, what we claim as new, and desire to secure by Letters Patent, is—

- 5 1. An apparatus for measuring, diluting and mixing chemicals for introduction into a washing-machine, comprising a mixing-cylinder, an agitator therein, a series of tanks for the chemicals located above said cylinder, pipes respectively connecting said tanks with said cylinder, cocks or cut-offs in said pipes, and a graduated measuring-tube for each of said tanks.
- 10 2. An apparatus for measuring, diluting and mixing chemicals for introduction into a washing-machine, comprising a mixing-cyl-
- 15 15

inder having valved inlet and discharge pipes, an agitator therein, a water-gage thereon, a series of tanks for the chemicals located above said cylinder, pipes respectively connecting said tanks with said cylinder, cocks or cut-offs in said pipes, and a graduated measuring-tube for each of said tanks.

In testimony whereof we have hereunto set our hands in presence of two subscribing witnesses.

HENRY G. IRMIGER.
JAMES McCARTHY.
